UNITED STATES PATENT OFFICE.

MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

ELECTRIC SWITCH.

1,193,380.

Specification of Letters Patent. Patented Aug. 1, 1916.

Application filed May 5, 1915. Serial No. 26,086.

To all whom it may concern:

Be it known that I, MONROE GUETT, a citizen of the United States, residing at Hartford, in the county of Hartford and State of Connecticut, have invented certain new and useful Improvements in Electric Switches, of which the following is a specification.

This invention relates to electric switches, the object of the invention being to provide an article of this character which is simple in construction, efficient in action and by which a plurality of electric devices can be simultaneously controlled.

15 The switch can be utilized with advantage in many different connections, one illustration of which is for controlling a range and at the same time a water heater, the construction being preferably such that one of these electric devices is always on while the other is off and vice versa.

20 In the drawings accompanying and forming part of the present specification I have illustrated in detail one of the several convenient forms of embodiment of the invention which to enable those skilled in the art to practise the same will be set forth fully in the following description. I do not restrict myself to this disclosure; I may 25 de-10 part therefrom in several respects within the scope of the invention defined by the claims following said description.

25 Referring to said drawings; Figure 1 is a top plan view of a switch involving my invention, the case for clearness, being omitted. Fig. 2 is a sectional plan view of said switch, the section being on the line 2—2 of Fig. 5. Fig. 3 is a sectional detail showing snap means. Fig. 4 is a similar 30 view, the section being on the line 4—4 of Fig. 3. Fig. 5 is an elevation partly in section of the switch, the section being on the line 5—5 of Fig. 1. Fig. 6 is a diagram illustrating the switch and certain circuit 35 connections.

40 Like characters refer to like parts throughout the several figures.

The switch comprises two switching members, a main switching member and an auxiliary switching member. The terms in question are employed merely for convenience and not with the intention of implying that one switching member is of greater importance than the other. Each switching member 45 controls the action of an electric device.

For example the main switching member can control the supply of current to a range, while the auxiliary switching member can subserve a like function with respect to a water heater, the organization being such that 50 when one of the switching members is on, the other is off and vice versa, so that current will always be flowing to one of said electric devices. While the switching members may be of any suitable character, they 55 are both shown as rotary. In like manner they may have one or any desired number of poles. In the present case the main switching member has three poles and the auxiliary switching member two. The main switching 60 member may be constructed like the switch shown in reissued Letters Patent No. 11,395, issued December 12, 1893 to G. W. Hart and to which reference may be had. This main switching member in the present case, therefore is snap operated by a suitable actuator such as a button or handle and through suitable means operates upon the auxiliary switching member all as will hereinafter 65 more particularly appear.

70 Referring now to Fig. 6, the numeral 10 denotes a meter intersected by the service wires 11 and 12 and 13 as common in installations of this character. The three wires after leaving the meter 10 are connected 75 with the contacts 14, 15 and 16 opposite the contacts 17, 18 and 19, the two series of contacts being arranged in coöperating pairs. The contacts 14 and 19, the contacts 15 and 80 18 and the contacts 16 and 17 respectively co-operate. From the contacts 17, 18 and 19 the conductors or wires 20, 21 and 22 lead, these constituting the load wires and being 85 connected to a range.

90 The several contacts just described constitute a part of the main switching mechanism. From the outer wires 11 and 13 on the service side of the meter 10 the wires 23 and 24 extend, being connected with the contacts 25 and 26. The contact 25 co-operates 95 with the contact 28 while the contact 26 co-operates with the contact 27, these contacts 25 to 28 inclusive constituting a part of the auxiliary switching mechanism. From the contacts 27 and 28 the service wires 29 and 100 30 extend and lead to a water heater. As will be inferred, I can use the switch in many connections and as an illustration have mentioned a water heater and a range. In the construction shown the current supplied to 105 110

the range is measured, whereas that supplied to the water heater is not. It will be clear that when the contacts 14, 15 and 16 and 17, 18 and 19 are electrically bridged as shown in Fig. 6 current will be supplied by way of the meter 10 to the range, the water heater at this time being cut out and the main switch member being on. When the main switching member is moved from on to off, the auxiliary switching member will simultaneously be moved from off to on so as to electrically bridge the contacts 25 and 28 and 26 and 27 respectively for supplying current to the water heater.

15 The different parts may be supported in any desirable manner, the insulating base or supporting body 31 being shown for this purpose. This body which may for instance be of porcelain constitutes a main support and carries the contacts 14 to 19 inclusive. The auxiliary support 32 also of insulating material such as porcelain or fiber carries the contacts 25 to 28 inclusive, being spaced or separated from the main support 31. As 20 shown this auxiliary support or disk 32 is fastened to blocks 33 rigid with the supporting body 31. The contacts 14 to 19 inclusive, are situated in the space between the main and auxiliary supports 31 and 32 and the commutator 34 of the main switching member is also located in this space. As shown the commutator 34 is provided with switch blades or pole pieces 35, the ends of which when the commutator 34 is 25 on enter between the branches of the clip-like contacts 14 to 19 inclusive.

30 The spindle is designated by 36, extending centrally through the commutator 34 and being supported by the body 31 for rotation. As a means for operating the spindle 36 it may be equipped with the insulating button 37. Associated with this spindle 36 is snap movement means of suitable kind as will hereinafter be set forth and which 35 is adapted when the spindle 36 has been advanced a certain distance under the primary action of the button or actuator 37 to cause a quick movement of the commutator 34 to move said commutator from off to on 40 or from on to off depending upon the position it occupied before the spindle 36 was initially turned.

45 The commutator for the secondary switching member is denoted by 38, the auxiliary support 32 having a chamber or counterbore 39 to receive said commutator which is suitably operated from the main commutator 34. The auxiliary commutator 38 has pole pieces or switch blades 40 to coöperate 50 with the contacts 25 to 28 inclusive. Said auxiliary commutator also has a suitable driving connection with the main commutator 34. As represented the auxiliary support 32 has a central hole 41 to receive the 55 pins 42 from the auxiliary commutator 38,

the cap plate of the main commutator 34 having perforations to receive the reduced ends 43 of said pins which constitute a convenient and simple way of connecting the two commutators for movement together.

Surrounding the spindle 36 is the coiled spring 45, connected respectively with the spindle and with the commutator 34. Rigid with the spindle 36 is the eccentric or cam 46 fitted in the central opening of the catch plate 47, the projection 48 of which coöperates with the stationary detent or rigid plate 49. When the spindle 36 is turned, the spring will be tensioned and at the same time the projection 48 will be moved out by the eccentric 46 acting upon the plate 47, the projection 48 being freed from the detent or ratchet plate 49 when the spring 45 has been tensioned sufficiently to impart a snap movement to the commutator 34 so as to move said commutator from on to off or from off to on depending upon its original position. When the commutator has moved the requisite distance, the projection 48 will enter a second notch of the detent or ratchet plate 49. The pole pieces 35 and the pole pieces 40 of the respective switching members or commutators 34 and 38 are insulated from each other and from the bodies or metal parts of the commutators as common in snap switches.

What I claim is:

1. An electric switch comprising a support, a switching member, the support having contacts coöoperative with said switching member, a second support, a second and independent switching member, the second support having contacts coöoperative with the second switching member and also having an opening, the second switching member having a driving connection with the first switching member through said opening, and manually operable snap means common to both switching members for effecting the simultaneous action thereof.

2. An electric switch comprising a support, a switching member, the support having contacts coöoperative with said switching member, means for moving the switching member between on and off positions, a second support, and a second and independent switching member, the second support having contacts coöoperative with the second switching member and also having an opening, the second switching member having a driving connection with the first switching member through said opening.

3. An electric switch comprising a support, a switching member, the support having contacts coöoperative with said switching member, means for moving said switching member between on and off positions, a second support, and a second and independent switching member, the second support having contacts coöoperative with the second

switching member and also having an opening, and pins connecting the two switching members and extending through said opening.

5 4. An electric switch comprising a switching member, a second and independent switching member, a manually operable spindle extending through the switching members, snap means actuated by the 10 spindle for moving the first switching mem-

ber between on and off positions, and means for moving the second switching member to off when the first switching member is moved to on and vice versa.

In testimony whereof I affix my signature 15
in presence of two witnesses.

MONROE GUETT
